UNITED STATES PATENT OFFICE.

JOHN W. ALLAN, OF MINNEAPOLIS, MINNESOTA, ASSIGNOR OF ONE-FOURTH
TO O. W. GETCHELL, ONE-FOURTH TO F. M. OVERHOLT, AND ONE-
FOURTH TO WILLIAM McMILLAN, OF MINNEAPOLIS, MINNESOTA.

SMOKE-CONSUMING FURNACE.

No. 799,960.

Specification of Letters Patent.

Patented Sept. 19, 1905.

Application filed April 22, 1905. Serial No. 256,830.

To all whom it may concern:

Be it known that I, JOHN W. ALLAN, of Minneapolis, Hennepin county, Minnesota, have invented certain new and useful Improvements in Smoke-Consuming Furnaces, of which the following is a specification.

This invention relates to improvements in boiler-furnaces; and the object I have in view is to provide means whereby in such a furnace a complete combustion of the fuel may be obtained.

Another object of the invention is to lessen the amount of fuel required to produce the desired steam-pressure in the boiler.

Other objects of the invention will appear from the following detailed description, taken in connection with the accompanying drawings, in which—

Figure 1 is a longitudinal vertical section 20 on the line xx of Fig. 2 of a boiler-furnace embodying my invention. Fig. 2 is a transverse vertical section on the line yy of Fig. 1. Fig. 3 is a front elevation of the same. Fig. 4 is a detail showing a modified arrangement 25 of the air-ducts.

In the drawings, 2 represents a tubular boiler of ordinary type; 3, the brickwork setting or furnace; 4, the grate; 5, the bridge-wall; 6, the ash-pit; 7, the fuel-doors, and 8, the ash-pit doors. All of these parts are of any preferred or ordinary construction.

Arranged above the grate and below the boiler is an arch 9, extending from the front of the combustion-chamber to a point above 35 the rear portion of the bridge-wall. This arch is preferably formed of suitable fire-brick and is provided with one or more longitudinal ducts or ports 10, extending from the front of the furnace to a point above the 40 rear end of the grate, where said ports are connected by suitable openings with the combustion-chamber of the furnace. Suitable dampers 11 are provided for regulating the admission of air to these ports. I have shown 45 the ports in Fig. 1 formed within the arch itself; but, if preferred, they may be embodied in separate conductors arranged in the space between the arch and the under side of the boiler, as shown in Fig. 4. I have shown 50 two of these ports or conductors, but do not limit myself to any particular number, as a greater or less number may be used, according to the requirements of any particular fur-

nace. The air entering these ports becomes highly heated before mingling with the products of combustion in the combustion-chamber. The space between the arch and the boiler, which I designate by reference-numeral 12, forms a flue or passage leading from the back end of the arch, between it and the 55 boiler, to the front end of the furnace, where it communicates with the chimney through ports 13, provided in the wall of the boiler. This passage allows the heated gases to pass through beneath the boiler to the said ports 60 and permits the entire heating-surface of the boiler to be utilized. When the gases reach the forward end of the passage, they will flow through the ports 13 and mingle with the waste gases that have entered at the rear end 65 of the boiler. The arch effectually separates the combustion-chamber from the bottom of the boiler and screens it from direct contact with the flames and prevents the deposit of particles of carbon thereon, but at the same 70 time does not reduce the heating-surface of the boiler. The bricks forming the arch will be heated to an incandescence, and the unconsumed particles of carbon coming in contact with the heated bricks will be raised to a high 75 temperature and traveling along said arch until they reach the point where the air is introduced through the ports 10 will mingle therewith and be immediately and completely 80 consumed. A much more perfect combustion 85 of the fuel is thereby obtained, and I have found that a large percentage of fuel can be saved in the production of a given amount of steam. I am also able to burn a poor grade 90 of soft coal without producing black smoke.

I claim as my invention—

1. The combination in a steam-boiler furnace with a combustion-chamber and grate and a bridge-wall located beneath the middle portion of the boiler, of an arch arranged over 95 said chamber and separating it from said boiler and extending from the front of said boiler to a point above the rear of said wall, there being a passage between said arch and boiler open at its rear end and communicating 100 at its forward end with openings leading to the chimney, whereby the heated gases are allowed to flow through said passage beneath the boiler and mingle with the gases which have entered the boiler at its rear end, and an 105 air-duct extending above the lower surface of

the arch from the front of the boiler and communicating with the combustion-chamber at a point above the rear of the grate, substantially as described.

5 2. The combination in a steam-boiler furnace with a combustion-chamber and a grate 4 and bridge-wall 5 located beneath the middle portion of the boiler, of an arch 9 arranged over said chamber and separating it from said 10 boiler and extending from the front of said boiler to a point above the rear of said wall there being a passage 12 formed between said arch and boiler open at its rear end and communicating at its forward end with openings 15 13 in the boiler-wall leading to the chimney

whereby the heated gases are allowed to flow therethrough beneath the boiler and mingle with those entering the rear end of the boiler, and air-ducts 10 provided above and on each side of the center of said arch and extending 20 from the front of the boiler to a point above said bridge-wall and communicating at said point with said combustion-chamber, substantially as described.

In witness whereof I have hereunto set my 25 hand this 13th day of April, 1905.

JOHN W. ALLAN.

Witnesses:

RICHARD PAUL,
C. MACNAMARA.
